Primary Examiner—Freda S Nunn*(74) Attorney, Agent, or Firm*—Rader, Fishman & Grauer, PLLC(57) **CLAIM**

The ornamental design for a computer monitor display, as shown and described.

DESCRIPTION

FIG. 1 is a perspective view of a first embodiment of a computer monitor display showing our new design;

FIG. 2 is a front elevational view thereof; and

FIG. 3 is a rear elevational view thereof.

FIG. 4 is a perspective view of a second embodiment of a computer monitor display showing our new design;

FIG. 5 is a front elevational view thereof; and

FIG. 6 is a rear elevational view thereof.

FIG. 7 is a perspective view of a third embodiment of a computer monitor display showing our new design, wherein the transparent button portion is at a first alternate position in connection with the first or second embodiment of FIG. 1 or 4;

FIG. 8 is a front elevational view thereof; and

FIG. 9 is a rear elevational view thereof.

FIG. 10 is a perspective view of a fourth embodiment of a computer monitor display showing our new design, wherein the transparent button portion is at a second alternate position in connection with the first or second embodiment of FIG. 1 or 4;

FIG. 11 is a front elevational view thereof; and

FIG. 12 is a rear elevational view thereof.

FIG. 13 is a perspective view of a fifth embodiment of a computer monitor display showing our new design, wherein the transparent button portion is at a third alternate position in connection with the first or second embodiment of FIG. 1 or 4;

FIG. 14 is a front elevational view thereof; and

FIG. 15 is a rear elevational view thereof.

FIG. 16 is a perspective view of a sixth embodiment of a computer monitor display showing our new design, wherein the transparent button portion is at a fourth alternate position in connection with the first or second embodiment of FIG. 1 or 4;

FIG. 17 is a front elevational view thereof; and

FIG. 18 is a rear elevational view thereof.

FIG. 19 is a perspective view of a seventh embodiment of a computer monitor display showing our new design, wherein the transparent button portion is at a fifth alternate position in connection with the first or second embodiment of FIG. 1 or 4;

FIG. 20 is a front elevational view thereof; and

FIG. 21 is a rear elevational view thereof.

FIG. 22 is a perspective view of an eighth embodiment of a computer monitor display showing our new design, wherein the transparent button portion is at a sixth alternate position in connection with the first or second embodiment of FIG. 1 or 4;

FIG. 23 is a front elevational view thereof; and,

FIG. 24 is a rear elevational view thereof.

The broken lines illustrate portions of the computer monitor display and form no part of the claimed design. The dot-dash broken lines surrounding the buttons shown in the drawings define, but are not included in the boundaries of the claimed design.
